TELEPHONE KEY SET CONFERENCE CALLER

Leopold A. Wenzler, 1008 Gordon Drive,
Decatur, Ala. 35601

Filed Apr. 19, 1971, Ser. No. 135,515

Term of patent 14 years

Int. Cl. D14—03

U.S. Cl. D26—14

FIG. 1 is a top plan view of a telephone key set conference caller showing my new design;

FIG. 2 is an elevational view showing one side thereof;

FIG. 3 is an elevational view showing the other side thereof;

FIG. 4 is an end elevational view looking from the right side of FIG. 1; and

FIG. 5 is an end elevational view looking from the left side of FIG. 1.

I claim:

The ornamental design for a telephone key set conference caller, as shown.
